UNITED STATES PATENT OFFICE.

ROBERT H. ADAMS. OF DETROIT. MICHIGAN.

VALVE FOR INTERNAL-COMBUSTION ENGINES.

1,053,894.

Specification of Letters Patent. Patented Feb. 18, 1913.

Application filed November 25, 1911. Serial No. 662,289.

To all whom it may concern:

Be it known that I, ROBERT H. ADAMS, a citizen of the United States, residing at Detroit, county of Wayne, State of Michigan, have invented a certain new and useful Improvement in Valves for Internal-Combustion Engines, and declare the following to be a full, clear, and exact description of the same, such as will enable others skilled in the art to which it pertains to make and use the same, reference being had to the accompanying drawings, which form a part of this specification.

This invention relates to valves for internal combustion engines and has for its object a valve comprising slotted sleeves one of which is divided into compartments. These sleeves reciprocate across the head of the cylinders and control both the inlet and 20 the exhaust ports.

In the drawings:—Figure 1, is a vertical section of the engine. Fig. 2, is a top view of the valve operating mechanism.

A, is a casting forming the cylinders 25 B, B¹ and forming the water jacket spaces C, C and lubricating conduits D, D, at the top of this casting. Traversing the cylinder heads B is a bore F in which are fitted the sliding sleeves H and G. The form of 30 engine shown in the casting A is of the two cylinder type and four cycle variety. In the cylinder B are located ports E and N, being the exhaust and the inlet ports, respectively, and these ports connect with the bore 35 F of the casting. Likewise, in cylinder B¹, near the top, are located the ports N¹ and E¹, being the inlet and the exhaust ports respectively, and connecting with the bore F of the casting.

40 The sleeves, of which H is the outer sleeve and G the inner sleeve, are the valves which control the exhaust and the inlet ports of the cylinders. The inner sleeve G is divided off into compartments by the partitions 1, 45 the middle compartment is the inlet compartment, while the end compartments are the exhaust compartments. If more than two cylinders are employed an exhaust compartment may do duty for two cylinders in 50 the same way as the middle inlet compartment operates. The exhaust compartment adjacent the cylinder B is put in communication with that cylinder, when the port e² of the sleeve H and the port e³ of the 55 sleeve G, each register with the port E into the cylinder. The compartment adjacent

the cylinder B¹ is put into communication with that cylinder, when the port e⁴ of the sleeve H and the port e⁵ of the sleeve G, each register with the port E¹ into the cylinder. The middle compartment or the inlet compartment, may be put into communication with either cylinder. Communication with cylinder B being effected by the registry of the port n² of the sleeve H and n³ of the sleeve G with the port N into the cylinder. Communication with the cylinder B¹ is effected by the registry of the ports n⁴ of sleeve H and n⁵ of sleeve G with the port N¹ into the cylinder.

70 The perforated brackets 2 and 3 are fast to the ends of the sleeves H and G, respectively. The connecting rod 4 connects the bracket 2 with the crank d on the counter-shaft 5, while the connecting rod 6 connects the bracket 3 with the crank e on the counter-shaft 5. These cranks are arranged 65 degrees from center to center. The counter-shaft 5 carries a bevel gear 7 that meshes with a bevel gear 8 on the shaft 9 that is operatively at half the crank shaft speed.

80 In Fig. 1, the sleeves, or valves, are shown as they are when the cylinder B has just exhausted and is about to enter upon the intake stroke, while the piston of the cylinder B¹ is on its working stroke. The bevel gear 7 on the shaft 5 is revolving clockwise, so that the sleeve H is at the limit of its travel away from the counter-shaft 5, while the sleeve G has yet to travel to its 85 limit away from the counter-shaft 5. The dotted lines show the position of the valves when the cylinder B is taking in gas, while the piston of the cylinder B¹ is on the working stroke. It will be noticed that the port n² and n³ register with the port N, so as to put the middle compartment of the valve into communication with the cylinder B. The inner sleeve G is also provided with 90 ports m, and the outer sleeve H with ports m¹. The ports m and m¹ of a particular compartment are in the form of elongated slots, so that a complete and unobstructed passage-way is afforded at all times from the manifold port m² into the cylinder.

100 In the dotted lines of Fig. 1, the position of the valves with respect to each other when the ports n² and n³ register with the port N, is shown. It will be noticed that all the rest of the ports are so out of registry and that each of the ports into the cylinder, except N, are cut off from the com- 105 110

partments, for at that moment the cylinder B is taking in gas, while the piston of the cylinder B¹ is on its working stroke. The placing of the ports and the arranging of 5 the reciprocation of the sleeves so as to bring the ports in the sleeves in registry at the proper time, is merely a matter of mechanical calculation, which I will not describe, as these would only be confusing, for 10 it is variable with the position of the port into the cylinder and the size of the port opening. Oil is supplied to the valve through the conduits D.

The form that I have shown in the drawings has the bore and the sleeves disposed across the center of the cylinder heads. However, the bore and the sleeves can be, 15 located on the side of the cylinder heads and still come within the spirit of my invention.

What I claim is:—

1. A valve for internal combustion engines, having in combination with a cylinder provided with an exhaust and an inlet 25 port, a pair of sleeves reciprocable across the head of the cylinder, a partition in the inner sleeve dividing the same into an exhaust and an inlet compartment, each sleeve being provided with a port leading into 30 each compartment, some of the ports of the sleeves being adapted to register with each other and the exhaust port into the cylinder, and the other ports adapted to register with each other and the inlet port into the 35 cylinder at predetermined periods, substantially as described.

2. A valve for internal combustion engines, having in combination with a cylinder provided with an exhaust and an inlet 40 port, a valve chamber or bore across the cylinder heads, provided with exhaust and inlet ports, a pair of sleeves reciprocable in said bore, partitions in the inner sleeve dividing the same into a closed inlet and a

closed exhaust compartment, each sleeve 45 being provided with a port leading into each compartment and registerable at predetermined periods with its companion sleeve port and the companion port leading into the cylinder, and each sleeve being provided with a port leading out of each compartment and registerable at predetermined periods with its companion sleeve port and the port in the bore leading from that compartment, substantially as described. 50 55

3. A valve for internal combustion engines, having in combination with a plurality of cylinders provided with ports, a pair of sleeves, each sleeve provided with ports and adapted to reciprocate across all 60 the cylinders, a plurality of partitions in the inner sleeve dividing the inner sleeve into compartments for inlet of gases and outlet of burnt gases, and valve operating gear for reciprocating the sleeves so that at 65 predetermined periods communication is established between each of the cylinders and an inlet compartment and an outlet compartment, substantially as described.

4. A valve for internal combustion engines, having in combination with a plurality of cylinders provided with ports, a sleeve reciprocable across all the cylinders, a plurality of partitions in said sleeve dividing the same into compartments for inlet 70 of gases and outlet of burnt gases, the sleeve being provided with ports leading into the compartments, and means for causing communication to be established between each cylinder and an inlet compartment and an outlet compartment at predetermined periods, substantially as described. 75 80

In testimony whereof, I, sign this specification in the presence of two witnesses.

ROBERT H. ADAMS.
